UNITED STATES PATENT OFFICE.

NIKITAS LAPPAS, OF PEABODY, MASSACHUSETTS.

PERMUTATION LOCK.

Application filed August 27, 1925. Serial No. 52,917.

To all whom it may concern:

Be it known that I, NIKITAS LAPPAS, a citizen of Turkey, residing at Peabody, in the county of Essex and State of Massachusetts, have invented certain new and useful Improvements in Permutation Locks; and I do declare the following to be a full, clear, and exact description of the invention, such as will enable others skilled in the art to 10 which it appertains to make and use the same.

This application forms a continuation in part of my allowed United States application Serial No. 750,394, filed November 17, 15 1924, and allowed July 7th, 1925.

Like the original application, one object of the invention is to provide an exceptionally simple and inexpensive, yet a highly desirable form of permutation or combination lock of the type in which a shaft is turned first in one direction and then in the other, to align certain locking members which must be so aligned before the lock can be released.

Further objects are to provide a novel dog and ratchet means for holding certain locking members in released position and to make provision whereby the locking members may be adjusted to change the combination of the lock.

The invention resides in the novel subject matter hereinafter described and claimed, for carrying out these objects, such matter being shown in the accompanying drawing.

Figure 1 is a plan view of a lock constructed in accordance with my invention.

Figure 2 is a longitudinal sectional view on line 2—2 of Fig. 1.

Figure 3 is a sectional view as indicated by line 3—3 of Fig. 2.

Figures 4, 5, 6, and 7 are perspective views showing different features of construction.

I have shown the improved locking mechanism in connection with an inner plate 1 secured by screws or the like 2 to a member A which is to be locked to another member B, and these members may be considered as

representing the body and cover of a container such as a trunk. Hinged to the member B, an outer plate 3 is shown, having a flange 4 to surround the plate 1. The two plates 1 and 3 are formed with depressed portions 5 and 6 respectively, whose centers are formed with openings 5^a and 6^a respec-

tively, the opening 5^a being in the shape of a key-hole.

A dial disk 7 spans the depression 6 and is provided on its lower side with a reduced portion 8 in said depression having ratchet teeth 9, these teeth being co-operable with a spring dog 10 secured in the aforesaid depression, so that the disk 7 may turn in one direction only. The portion 8 is provided with an integral sleeve 11 passing through the opening 6^a, and when the plates 1 and 3 are engaged, through the opening 5^a also, said sleeve carrying a locking member 12.

The outer side of the disk 7 is formed with a recess 13 containing a spring dog 14, the latter being co-operable with ratchet teeth 15 on the inner side of a disk 16 which spans said recess 13. This disk 16 is provided at its inner side with an integral sleeve 17 projecting through the sleeve 11 and carrying a locking member 18. The outer side of disk 16 is formed with a substantially annular channel 19 interrupted by an abutment 20 so that it is of non-continuous form. This channel is spanned by a dial disk 21 having an integral shaft 22 which projects through the sleeve 17 and carries a locking member 23. This disk 21 is provided with an operating knob 24 by means of which it may be rotated, and said disk is also provided with a projection 25 received in the channel 19 to co-act with the latter and the abutment 20, (forming the channel ends) in establishing a lost motion connection between the disks 21 and 16.

The locking members 12, 18 and 23 are in the form of arms projecting from rings 12^a, 18^a and 23^a respectively, said rings surrounding the sleeves 11 and 17 and shaft 22 respectively. The sleeves 11 and 17, have circumferentially spaced notches 11^a and 17^a, any of which may receive keys 12^b—18^b on the rings 12^a and 18^a, permitting the combination of the lock to be readily varied. The ring 23^a is preferably non-adjustably keyed to shaft 22 by a key 23^b fitting into a key-way 22^a.

All parts are held in assembled relation by a single screw 26 threaded into the inner end of the shaft 22, and washers 27 may be used wherever desirable.

The plate 3 and disk 7 have suitably identified indicators 3^a and 7^a and disk 21 is provided with an indicator 21^a. By first turning disk 7 in the direction permitted by

dog 10 and teeth 9, until the predetermined relation exists between the indicators 7^a and 3^a, the locking member 12 is set at released position with respect to the opening 5^a. Then, by turning knob 24 in the proper direction, its disk 21 turns the disk 16 in the direction allowed by the ratchet 14—15, the ratchet 9—10 then holding disk 7 against accidental movement. When knob 24 has been turned until the predetermined relation of indicators 21^a—7^a, exists, the locking member 18 will have been alined with member 12. The knob 24 is retrogradely turned to the proper extent to 15 aline the locking member 23 with the members 12 and 18, and during this movement, ratchet 14—15 holds the disk 16 and sleeve 17 against accidental movement. With the three members 12, 18 and 23 alined, they 20 may pass through opening 5^a and permit separation of plate 3 from plate 1, allowing relative movement of the members A and B.

It will be seen from the foregoing that a 25 very simple and inexpensive, yet an efficient and desirable permutation lock has been provided. As excellent results may be obtained from the details disclosed, they may well be followed, but within the scope of the invention as claimed, numerous modifications 30 may be made. Moreover, the lock may be used in connection with a great many different articles, as will be readily understood.

I claim:—

- 35 1. A permutation lock comprising a shaft, a locking member on and operable by said shaft, a sleeve rotatably mounted on the shaft and having a series of circumferentially spaced recesses, a second locking member, means on said second locking member for engaging the recesses in said sleeve whereby the second locking member may be adjusted on the sleeve for changing the combination of the lock, and a lost-motion driving connection between said shaft and sleeve.
- 40 2. A permutation lock comprising a shaft having a dial disk at one end, a sleeve rotatably surrounding said shaft and having a disk contacting with the inner side of the first named disk, one of said disks having a non-continuous concentric channel and the other disk having a projection received in said channel, said disks, said channel and

said projection forming a lost-motion driving connection between the shaft and sleeve, and locking members carried by said shaft and sleeve respectively.

3. A permutation lock comprising a shaft having a locking member to be turned thereby, a sleeve rotatable on said shaft and having a second locking member, a lost-motion driving connection between said shaft and said sleeve, a ratchet wheel secured to the sleeve, and a dog co-operable with said ratchet wheel to hold the sleeve when set at a predetermined position by the aforesaid shaft and driving connection.

4. A structure as specified in claim 2; together with ratchet teeth on the edge of the second disk, and a dog co-acting with said teeth to hold the sleeve when set at a predetermined position by the aforesaid shaft and driving connection.

5. A permutation lock comprising a stationary plate having an irregular-shaped opening, a movable plate having an opening 75 for alinement with the first named opening, said movable plate having a depressed portion in the bottom of which its opening is formed, a dial disk spanning said depressed portion and having a ratchet wheel portion 80 located in the depression, a dog mounted in said depression and co-acting with the ratchet teeth, a sleeve projecting from the inner side of the disk through the openings of the two plates and provided with a 85 laterally extending locking member to engage the first named plate, the outer side of said disk having a recess and a dog therein, another disk within this recess having ratchet teeth co-operable with the dog, a 90 sleeve projecting from the second-named disk through and beyond the first named sleeve, a second locking member on the inner end of the second sleeve, a third disk spanning the recess of the first named disk and 95 having a lost motion driving connection with the second named disk, a shaft passing from said third disk through the second named sleeve and projecting beyond the latter, and a third locking member projecting laterally 100 from the inner end of said shaft.

In testimony whereof I have hereunto affixed my signature.

NIKITAS LAPPAS.
